UNITED STATES PATENT OFFICE.

JOHN HARVEY PEARSON, OF INDIANAPOLIS, INDIANA, ASSIGNOR TO ONEPIECE BIFOCAL LENS COMPANY, OF INDIANAPOLIS, INDIANA, A CORPORATION.

RECIPROCATING LENS-SURFACING APPARATUS.

1,317,453.

Specification of Letters Patent. Patented Sept. 30, 1919.

Application filed February 28, 1917. Serial No. 151,601.

To all whom it may concern:

Be it known that I, JOHN HARVEY PEARSON, a citizen of the United States, and a resident of Indianapolis, county of Marion, 5 and State of Indiana, have invented a certain new and useful Reciprocating Lens-Surfacing Apparatus; and I do hereby declare that the following is a full, clear, and exact description thereof, reference being 10 had to the accompanying drawings, in which like numerals refer to like parts.

The object of this invention is to improve the construction and operation of apparatus for grinding and polishing lenses of the 15 character of that shown in Letters Patent to Charles W. Conner, No. 1,162,039, patented November 30, 1915. The particular purpose for which such machines have been heretofore used has been to polish bifocal lenses.

20 As shown in said previous patent, the pin for holding the polishing button or element is stationary in operation, after it has been adjusted and set in the right angle or position. The purpose of this invention is to 25 enable the polishing button or element to be oscillated automatically transversely of the blank or lens being treated.

The object and effect of this transverse oscillatory movement of the polishing element 30 is to polish and treat the lens or blank more effectively. For instance, often the first or preliminary polishing element with which the ground blank is treated, leaves the center of the inner and the minor or 35 reading surface rough, incomplete or elevated, because such polishing element operates around such point of the lens as a center. Afterward the lens blank is operated on by the polishing apparatus herein 40 shown and the polishing element for the inner, minor or reading surface travels or oscillates laterally as they are doing the polishing operation so as to smooth, complete and polish said central portion of such 45 inner, minor or reading surface.

To understand this, it must be borne in mind that in making such bifocal lenses, the blank is ground and polished with the central circular, minor or reading surface surface 50 rounded by an outer annular, major or distance surface, and afterward the blank is centrally split to make two lenses. However, instead of a single piece of glass, ground and polished as explained and afterward split in two for two lenses, a plurality 55

of pieces of glass may be secured on the lens holder, one for each lens, and be ground and polished, the same as a single piece of glass.

This invention is of particular value, 60 however, in making those types of bifocal lenses having a relatively large minor or reading surface. That may be in small sized lenses having a large reading surface, say 3 1 mm. in size, and also the "jumbo" or 65 relatively large bifocal lenses which likewise have said large minor or reading surface. In these two types of lens blanks, the minor or reading surface extends beyond the center of the blank as it is ground and 70 polished, and it is desirable that said central roughness, projection or elevation be polished away in order to make said minor or reading surface of the bifocal lens smooth, 75 complete and perfect.

The chief feature of the apparatus whereby this object is accomplished consists in a double pivoted means for carrying the pin which holds the polishing element, whereby it may be moved laterally as well as vertically, and also in associating therewith a cam or other means for causing the lateral oscillatory movement of the pin or means 80 for holding the polishing element.

The full nature of the invention will be 85 understood from the accompanying drawings and the following description and claims.

In the drawings, Figure 1 is a side elevation of the machine showing means for 90 carrying the pin which holds the polishing element in substantially a vertical position. Fig. 2 is a plan view of the machine shown in Fig. 1, excepting that the upper part of the pin and the weight thereon are cut away. 95 Fig. 3 is a section on the line 3—3 of Fig. 2, with parts broken away. Fig. 4 is a section through the polishing element and the lens holder and a lens, showing the polishing button in one position by full lines and in another position by dotted lines. Fig. 5 is a section on the line 5—5 of Fig. 1. Fig. 6 is a front elevation of a part of the machine showing a modified form with the pin mounted in angular position and for holding 100 and operating a large button or element for polishing the outer annular long-distance surface of the lens. Fig. 7 is a figure similar to that of Fig. 6, showing, however, the pin carrying a polishing button or element 105 110

for treating the central, minor or reading surface of the lens.

In the drawings there is shown herein a base plate 10 with a vertical shaft bearing 11 for a shaft 12, shown by dotted lines in Fig. 1 and by full lines in Fig. 2. On this shaft there is a pulley 13 driven by a belt 14 from some suitable source of power. It is immaterial how this part of the mechanism is constructed.

On the shaft 12 there is a sprocket wheel 112, over which a sprocket chain 15 operates and transmits power to a sprocket wheel 116, on an arbor 16 that carries the lens holder 17 on which the lens blank 18 is mounted.

On the table 10 there are two bearing posts 20 and 21 which carry adjustable center pins 22 for mounting a substantially triangular frame 23 which extends forwardly from said bearing to a point near the lens holder and so that the latter end of said frame may be lifted up or let down, substantially the same as the corresponding portion of said previous patent to Charles W. Conner. The front free end of said frame has a straight radially and vertically extending surface 25 as seen by dotted lines in Fig. 2 and full lines in Fig. 6. Besides said surface 25 of frame 23 there is mounted a vertical pin 26 which holds or operates the polishing button or element 27. The pin extends loosely through a brass bushing or sleeve 28 which is rigidly secured and clamped in a clamping head 29. This clamping head extends vertically and is mounted by a screw 30 in a head 31 whereby the clamping head 29 and the pin 26 may be adjusted from the truly vertical position, as shown in Fig. 1, to the angular position shown in Figs. 5 and 6. The pin 26 has secured upon its upper end the usual weighting apparatus 32.

The head 31 is secured to the forward up-turned end 33 of a bar 34, which has a vertical rear end, as seen in Fig. 3, that is mounted on a lower bearing pin 35 and adjustable upper bearing pin 36. The bearing pin 35 is mounted in the wide portion of the triangular frame 23 and the upper adjusting pin 36 is secured in an arm 37 extending from said frame 23. This enables the head 29 carrying the pin 26 for holding the polishing element 27 to have lateral movement.

The lateral movement of said pin 26 is effected by a cam 40, shown in full lines in Figs. 6 and 7 and by dotted lines in Fig. 2. This cam is a disk through which the pin 26 extends loosely and eccentrically and said cam is mounted at the same elevation as the free end of the frame 23 so that its periphery may bear against the straight surface 25 of said frame, as shown in Figs. 2, 6 and 7. Said cam is held against the sur-

face 25 by a spring 45, one end of which is secured to the bar 24 and the other to a bracket 46 on the frame 23. Such movement of the frame 23 and cam 40 by said spring is limited by an adjusting screw 47 mounted in a bracket 48 on the frame 23. The cam 40 is turned by a pulley 50 secured on a sleeve 51 which is secured to said cam. The pulley is driven by a belt 52 running from a pulley 53 on a shaft 54 in bearings 55 in a bracket 56 mounted upon the base plate 10. The shaft 54 has a gear 57 on its lower end which is driven by a gear 58 on the upper end of the shaft 12.

In operation the lens holder is positively rotated by the chain 15. The polishing button or element 27 rests upon the lens blank and is held there by the pin 26 and the weight thereon and the pin is held in a truly vertical or angular position by the clamping head 29 and means by which it is carried. The polishing element 27 is given lateral oscillatory movement by the cam 40 as it is turned by the belt 52 and pulley 50 and it bears against the surface 25 of the frame 23 and is held against said surface by the spring 45. The transverse movement of the polishing element 27 is limited by the size and arrangement of the cam 40 and also by the adjusting stop 47.

The machine, as a lens polisher in the manufacture of bifocal lenses, is adapted to polish either the outer annular distance surface or the inner minor or reading surface of the lens blank. The polishing element 27, shown in Figs. 1 and 5, is for polishing the outer or distance surface and has an annular polishing rib on the underside thereof, as shown in Fig. 6, having a diameter which enables the rib to span at all times the inner-reading surface without engaging it. As the machine operates, the lateral movement of the polishing tool moves it transversely from the position shown by full lines in Fig. 5, where it is at its right hand limit of movement and, therefore, the right hand edge of said rib near the right hand edge of the lens and the left hand edge of said rib is at the left hand edge of the inner or reading surface and on a dividing line between the two surfaces. Therefore, while said polishing element is polishing said outer annular distance surface, it is traveling laterally to and fro across the lens for a distance equal to the width of the one side of said annular distance surface.

In Fig. 6 it is desired to show that by adjusting the screw 47 so that the side of the oscillatory bar 34 is always in engagement with said screw, the cam 40 can then be held in such a position that it will not engage the side 25 of the triangular frame 23. Thus the polishing of the lens is done in the old manner, namely, holding a polishing element 27 in engagement with a rotating lens, as is

done in the afore-mentioned Conner Patent No. 1,162,039.

Fig. 7 shows the same form as in Fig. 6, excepting the polishing element 64 is differently formed, being a plain button which engages and polishes only the inner or reading surface.

The invention claimed is:

1. A lens surfacing apparatus including a lens holder, a surfacing element for treating a lens on said holder, means for holding said surfacing element in engagement with the lens on said holder and which means is pivotally mounted so as to be reciprocable transversely of said lens holder, a fixed means and means carried by said surfacing element holder and engaging said fixed means for causing and controlling the limits of such transverse movement.
2. A lens surfacing apparatus including a lens holder, means for holding a surfacing element in engagement with the lens on said holder, one of said members being mounted so as to be reciprocable transversely of the other member, a rotatable eccentric disk carried by said reciprocable member, and an adjustably fixed stop which the periphery of said eccentric disk engages, whereby the means for holding the surfacing element will be reciprocated transversely of the lens holder.
3. A lens surfacing apparatus including a lens holder, means for holding a surfacing element in engagement with a lens on said holder and arranged to be reciprocable transversely of the lens holder, a rotatable eccentric loosely mounted on the means for holding the surfacing element, and an adjustable fixed stop which one side of said eccentric engages, whereby the means for holding the surfacing element will be reciprocated transversely of the lens holder.
4. A lens surfacing apparatus including a lens holder, a surfacing element, means for holding said surfacing element in engagement with the lens on said holder and which means is pivotally mounted so as to be free to move toward and away from the lens holder and also transversely thereof, a fixed means and a rotatable eccentric mounted on the surfacing element holder and tangentially engaging said fixed means for causing and controlling the limits of such transverse movement.
5. A lens surfacing apparatus including a lens holder, a surfacing element in engagement with the lens on the holder and which is mounted so it can be moved transversely of the lens holder, an eccentric loosely mounted on said pin, means for rotating the eccentric, and fixed means against which said eccentric at one side bears during its operation and whereby the pin is given transverse movement.
6. A lens surfacing apparatus including a lens holder, a surfacing element, a pin for holding said surfacing element, a frame in which the pin is mounted and which is pivotally mounted so that the pin will be capable of movement transversely of the lens holder, and means carried by the pin for causing such transverse movement.
7. A lens surfacing apparatus including a lens holder, a lens surfacing element, a pin for holding said surfacing element, a frame in which said pin is mounted and which frame is pivoted so that it will be free to swing transversely of the lens holder, yielding means tending to move said frame in one direction, means for limiting such movement, and means for moving the frame in the opposite direction, whereby the surfacing element will be caused to move within limits transversely of the lens holder.
8. A lens surfacing apparatus including a lens holder, a lens surfacing element, a pin for holding said surfacing element, a frame in which said pin is mounted and which frame is pivoted so that it will be free to swing transversely of the lens holder, an eccentric mounted on said pin, a fixed surface which said eccentric engages, whereby it will move the pin transversely of the lens holder, means for rotating said eccentric, yielding means tending to move said frame so that the eccentric will engage said fixed surface, and an adjustable stop for limiting such movement of said frame.
9. A lens surfacing apparatus including a lens holder, a lens surfacing element, a pin for holding said surfacing element, a frame in which said pin is mounted and which frame is pivoted so that it will be free to swing transversely of the lens holder, an eccentric mounted on said pin, means for rotating said eccentric, a frame pivoted so as to be vertically oscillatory and projecting beside said eccentric and upon which frame said pin carrying frame is pivoted, a spring carried by said second frame tending to move the eccentric on said pin carrying frame toward said second frame, and a screw stop on said second frame in position to limit the movement of the pin carrying frame.

In witness whereof, I have hereunto affixed my signature.

JOHN HARVEY PEARSON.
